UNITED STATES PATENT OFFICE

WILLIAM J. DRAIN, JR., OF PHILADELPHIA, PENNSYLVANIA.

DESIGN FOR A JEWELRY-DISPLAY STAND.

SPECIFICATION forming part of Design No. 35,748, dated February 18, 1902.

Application filed January 20, 1902. Serial No. 90,590. Term of patent 3½ years.

To all whom it may concern:

Be it known that I, WILLIAM J. DRAIN, Jr., a citizen of the United States, residing in Philadelphia, Pennsylvania, have invented and produced a new and useful Design for a Jewelry-Display Stand, of which the following is a specification.

My design for a jewelry-display stand is clearly shown in the accompanying drawings, in which—

Figure 1 is a perspective view of the stand, and Fig. 2 is an elevation of the same.

My design consists of a display-stand having a rounded body and a base joined by a contracted neck, the rounded body having perforations disposed in the upper portion of the same.

In the drawings, 1 represents the rounded body; 2, the base; 3, the contracted neck joining the body and base portions; 4 and 5, the shoulders of the contracted neck, and 6 the perforations of the body.

I claim—

The design for a display-stand, substantially as described and as shown in the accompanying drawings.

In testimony whereof I have signed my name to this specification in the presence of two subscribing witnesses.

WM. J. DRAIN, JR.

Witnesses:

MURRAY C. BOYER,
JOS. H. KLEIN.
